CLAIM

The ornamental design for a baby bottle, as shown and described.

DESCRIPTION

FIG. 1 is a top, right perspective view of a baby bottle, shown in a first configuration wherein the cap is affixed to the top of the bottle;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, right perspective view of the baby bottle of FIG. 1, shown in a second configuration wherein the cap is affixed to the bottom of the bottle.

In the drawings, the broken lines depict environmental subject matter and form no part of the claimed design.
